FREEZING DEVICE

Edmund F. Schweller, Dayton, Ohio, assignor to General Motors Corporation, Detroit, Mich., a corporation of Delaware

Application December 6, 1954, Serial No. 473,107

2 Claims. (Cl. 62—108.5)

This invention relates to freezing devices for use in 15 household refrigerators to produce small ice blocks.

An object of my invention is to provide an improved freezing device of the tray and grid type wherein fast freezing characteristics of a metal tray are retained while ice blocks frozen in compartments of the device are 20 readily and quickly removed therefrom in a novel fashion.

Another object of the invention is to provide a freezing device from which single ice blocks may be successively and selectively harvested without disturbing other blocks 25 therein and leaving these other blocks bonded to walls of the grid and tray of the device for future harvesting therefrom.

A further object of my invention is to provide a low-cost freezing device including a substantially rigid sheet metal tray and a grid structure therein forming ice block compartments from which ice blocks are removable by pressure applied thereto by a person's finger through a movable resilient member forming a part of the upright tray side walls.

A still further and more specific object of my invention is to provide a freezing device including a sheet metal tray having ice block freezing compartments therein each provided with an inclined wall having an opening therein closed by a flexible resilient member secured to the edge portion of the tray bounding the opening and which member is thrustable against an ice block in the compartment by pressure applied thereto by one's finger for loosening a single ice block from walls of the compartment and for elevating the single loosened block relative to the tray while leaving other ice blocks in the device bonded to walls of their compartment.

Further objects and advantages of the present invention will be apparent from the following description, reference being had to the accompanying drawings, wherein preferred forms of the present invention are clearly shown.

In the drawings:

Figure 1 is a perspective view of an ice freezing device having my invention embodied therein.

Figure 2 is an enlarged vertical sectional view taken on the line 2—2 of Figure 1 showing an ice block in the freezing device and resilient rubber-like membranes in the upright side walls of the tray of the device.

Figure 3 is a view similar to Figure 2, with resilient membranes of the device flexed relative to walls of the tray and showing an ice block loosened from walls of the device and elevated from its compartment.

Figure 4 is a perspective view of a modified form of ice freezing device showing a grid structure disposed in the tray thereof.

Figure 5 is an enlarged vertical sectional view taken on the line 5—5 of Figure 4 showing ice blocks in the device, a tapered longitudinal wall of the grid therein and resilient rubber-like membranes in side walls of the tray thereof.

Figure 6 is a view similar to Figure 5 showing an ice block loosened from its compartment walls and elevated

2

relative to the grid and tray of the modified form of freezing device.

Figure 7 is a sectional view taken on the line 7—7 of Figure 4 showing an interlocking connection between intersecting walls of the grid structure in the modified form of freezing device.

Referring to the drawings, for illustrating the present invention, I have shown in Figure 1 thereof an elongated rigid relative narrow tray or pan stamped in one piece from sheet metal. This tray has a substantially flat bottom wall 11, end walls and upright side walls 12. Sheet metal side walls 12 of the tray are inclined outwardly from the bottom to the top thereof. A rolled over rim 14 formed integral on the tray extends continuously around the top thereof to increase its structural strength and prevent deformation of same. A plurality of longitudinally spaced apart grid or partitioning walls 16 extend transversely across the tray and divide the interior thereof into a plurality of ice block freezing cells or compartments 17 or a row of such compartments in which water is to be frozen into ice blocks indicated at 18 (see Figures 2 and 3). The cross walls 16 are rigidly secured to the tray in parallel relationship to one another by welding or brazing the same to its bottom 11 and upright side walls 12. Each of the inclined side walls 12 of the tray is provided with a row of substantially round openings therein disposed at the sides of compartments 17. The metal of the tray bounding each opening in the side walls thereof is flanged outwardly as at 21 to provide a depression in the tray side walls surrounding the round openings therein. This offsets the edge portions of the openings laterally with respect to the inclined tray side walls 12. A flexible resilient non-metallic rubber-like membrane, thin round disc or button member 22 is disposed in each opening in the side walls 12 of the tray and seals the openings. Each member 22 is provided with a groove 23 extending continuously around its edge and when the members 22 are forced into the openings in the tray walls, this groove 23 fits over and is interlocked with the offset edge portion of the sheet metal sides of the tray bounding the openings therein. The flexible and resilient rubber-like membranes or button members 22 may be formed of an elastomer such as butadiene-acrylonitrile copolymer, polychloroprene, etc., which materials are readily bonded to metal by methods now conventional and well known to those skilled in the art. Thus the flexible members 22 in addition to being mechanically interlocked in position in the openings in the tray side walls 12, by the grooves 23, may also be bonded to the metal tray walls about the openings therein to insure a water tight seal thereof and to prevent the members 22 from being accidentally detached from the ice tray. The inner portion of each rubber-like member 22 fills the depression on

the inside of tray side walls 12 adjacent each opening therein and the inner surface thereof is flush with the inner surface of these side walls so as to provide an unobstructed substantially smooth inner wall surface at opposite ends of the ice block compartments 17. The rubber-like membranes 22 form push buttons adapted to be flexed by pressure of one's finger to apply a thrust-like force to any one ice block 18 for a purpose to now be described.

After water placed in the tray of the freezing device, shown in Figure 1 of the drawings, has been completely frozen into the ice blocks 18 in a refrigerator cabinet the freezing device is removed from the cabinet for permitting the harvesting of a single selected ice block or the successive harvesting of a plurality of ice blocks from the freezing compartments 17 in the device. In order to accomplish the removal of an ice block 18 one of the rubber-like membrane members or buttons 22 on one side of

the tray or both of them on opposite sides of the tray is or are manually compressed in a direction inwardly of a compartment 17 against the ice block 18 therein by the pressure of one's fingers. This force applied to an ice block 18 initially breaks a bond between same and walls of its compartment 17 and continued force applied by the fingers to the button members 22 thereafter pushes the buttons laterally into the compartment and thrusts the loosened ice block 18 upwardly within its compartment 17 whereupon it slides along the walls 16 to move a top portion thereof above the top of walls 16 (see Figure 3). The single loosened elevated ice block 18 may be grasped by the fingers of a person's hand or by suitable ice tongs for harvesting it from the device. Obviously as many ice blocks as are desired may be successively removed one at a time by repeating the operation just described along the length of the tray. By engaging opposed buttons 22 and simultaneously applying force thereto the task of releasing an ice block is greatly reduced and can be carried out with ease. The ice blocks to be removed are harvested from the device without disturbing other of the ice blocks 18 therein, to thereby leave these other ice blocks bonded to walls of their compartments.

In Figure 4 of the drawings there is shown a somewhat modified form of freezing device in which the principle of my invention is employed. In this showing a rigid walled grid structure is disposed in an elongated sheet metal tray and is removable therefrom as a unit so as to facilitate cleaning of the grid and tray. The rigid sheet metal tray in this modified showing is substantially like the tray I have disclosed in Figures 1 to 3 of the drawings but is slightly wider in order that walls of the unitary grid disposed therein may partition or divide the interior of the tray into two rows of ice block freezing compartments. The tray in the modification shown in Figure 4 includes a flat bottom wall 11A, end walls, upright outwardly inclined side walls 12A and an integral rolled over rim 14A at the top thereof extending continuously around the tray. The inclined upright tray side walls 12A are provided with a row of substantially round openings flanged outwardly as at 21A. A resilient rubber-like membrane or button member 22A, similar in all respects to the member 22, is provided with a continuous groove 23A which fits over the offset walls of each of the openings in the tray side walls. The members 22A fill each depression on the inside of tray walls 12A adjacent the openings therein so as to provide smooth unobstructed wall surfaces on opposite sides of the tray. The rubber-like members 22A, like members 22, form push buttons adapted to be manually flexed by pressure of one's fingers to apply a thrust force to an ice block 18A for the purpose of removing an ice block 18A from this modified form of freezing device. The removable grid structure in this modified device includes a rigid longitudinal wall 31 and a plurality of spaced apart rigid parallel walls 32 extending transversely thereacross and across the tray to divide the interior of the tray into rows of ice block freezing cells or compartments 33 in which water is to be frozen into ice blocks. The longitudinal grid wall 31 is tapered outwardly from the top to the bottom thereof (see Figure 5) to provide this wall with inclined surfaces for the ice block compartments 33. Transverse walls 32 are preferably, although not necessarily, provided with flat surfaces which are parallel to one another. A web part 36 (see Figure 7) of each transverse wall 32, above a slot provided therein, fits in a slot 37 cut in the tapered longitudinal wall 31. These walls 31 and 32 are staked or otherwise suitably secured together at their intersection with one another as is now conventional and well known in the art.

After water is frozen into the ice blocks 18A in the modified freezing device disclosed in Figure 4 of the drawings this device is removed from the refrigerator cabinet for permitting the harvesting of a single selected ice block 18A or the successive removal of a plurality of the ice blocks one at a time from compartments 33 of the de-

vice. One of the membranes or button members 22A on one side of the tray is manually compressed in a direction inwardly of a compartment 33 against an ice block 18A by the pressure of one's finger. This applies a thrusting force to the ice block which breaks the bond between same and walls of its compartment 33. Continued force applied to the now loosened ice block 18A pushes the buttons laterally into the compartment and causes same to elevate an ice block 18A in its compartment 33 relative to the tray end grid whereby the block 18A slides upwardly along the inclined partitioning wall 31 to shift a portion thereof above the grid walls 31 and 32 (see Figure 6). This single loosened and elevated ice block 18A may be grasped by the fingers or by suitable ice tongs and removed from the freezing device. As many ice blocks 18A as are desired may be removed one at a time in succession by repeating this ice block harvesting manipulation of the buttons 22A along the length of the tray. The removed ice blocks are harvested from the device without disturbing other of the ice blocks 18A therein whereby these other blocks remain in the device bonded to walls of compartments therein. It is to be understood that if two end to end ice blocks in this modified device is desired to be harvested together therefrom the fingers of one's hand may be placed in straddling relation to the tray so as to simultaneously engage and apply a force to the button members 22A on opposite sides of the tray whereupon two transversely opposed ice blocks 18A will be loosened from their compartment walls and slid upwardly thereof along the tapered surfaces of the longitudinal grid wall 31.

The openings in walls of the trays of the devices disclosed are effectively sealed by the membrane or button members 22 and 22A and the resiliency of these flexible members causes them to assume their original normal position, as shown in Figures 2 and 5 of the drawings, when the fingers of one's hand are released therefrom. A simple and inexpensive freezing device is thus provided and my invention permits retention of the fast freezing characteristics of a metal tray while at the same time providing for the quick and easy removal of one or more ice blocks from the device. Bonding of the rubber-like membrane or button members 22 and 22A to the metal trays is preferred so as to prevent these members from becoming loose and being removed from the tray. Ice cubes or blocks can be harvested from my improved freezing device without application of heat thereto and without manipulating grid wall moving levers, etc., which tend to increase the manufacturing cost of such freezing devices.

While the embodiments of the present invention as herein disclosed, constitute preferred forms, it is to be understood that other forms might be adopted.

What is claimed is as follows:

1. A freezing device comprising, an elongated sheet metal tray provided with a row of compartments in which water is to be frozen into separated ice blocks, said tray having an uninterrupted continuously flat bottom adapted to be supported on a freezing member whereby to retain the fast freezing characteristics of the metal tray, at least one wall of each of said compartments being inclined outwardly from said bottom of the tray to the top thereof, an upright side wall of said tray having spaced apart openings therein each opposed to the said one wall of said compartments, the edge portion of said tray side wall adjacent openings therein being flanged outwardly and forming a depression therein, a resilient membrane in each opening in said tray side wall and interlocked with said edge portion of said openings, said membranes filling said depressions and having their inner surface flush with the inner surface of said tray side wall, said membranes being exposed at a side of said tray, said membranes being manually flexed one at a time in succession throughout the length of said tray toward an inclined wall of a compartment to selectively pry a single ice block thereagainst,

and said prying action shifting said single ice block in a straight line direction upwardly along said inclined wall to position a portion of said single ice block above a compartment wall while leaving other ice blocks in said device bonded to said tray.

2. A freezing device comprising an elongated metal tray having an uninterrupted continuously flat bottom adapted to be supported on a freezing member whereby to retain the fast freezing characteristics of the metal tray, a grid structure disposed in said tray and removable therefrom, said grid structure including a longitudinal wall and a plurality of spaced apart walls extending transversely thereacross to divide the interior of said tray into rows of compartments in which water is to be frozen into separated ice blocks, said longitudinal grid wall being tapered outwardly from the top to the bottom thereof to provide inclined wall surfaces opposing each upright long sides of said tray, the upright long sides of said tray having an opening therein at each of said compartments defined by said transverse grid walls, the edge portion of said tray sides adjacent openings therein being flanged outwardly and forming a depression therein, a resilient membrane in each opening in said tray sides and inter-

locked with said edge portion of said openings, said membranes filling said depressions and having their inner surface flush with the inner surface of said tray sides, said membranes being exposed at sides of said tray, said membranes being manually flexed one at a time in succession throughout the length of said tray toward one of said inclined surfaces of said tapered longitudinal grid wall therein to selectively pry a single ice block thereagainst, and said prying action shifting said single ice block in a

10 straight line direction upwardly along said inclined longitudinal grid wall surface to position a portion of said single ice block above said grid walls while leaving other ice blocks in said device bonded to their compartment walls.
